UNITED STATES PATENT OFFICE.

RICHARD H. ALLAN, OF CHARLESTON, SOUTH CAROLINA.

DESIGN FOR A BADGE, BUTTON, PIN, OR SIMILAR ARTICLE.

49,943.

Specification for Design.

Patented Nov. 28, 1916.

Application filed September 28, 1916. Serial No. 122,770. Term of patent 7 years.

To all whom it may concern:

Be it known that I, RICHARD H. ALLAN, a citizen of the United States, residing at Charleston, in the county of Charleston and State of South Carolina, have invented a new, original, and ornamental Design for a Badge, Button, Pin, or Similar Article, of which the following is a specification, reference being had to the accompanying drawing, forming a part thereof.

The figure is a front view of a badge showing my new design, the parts being lined to show the red and blue colors.

I claim:

The ornamental design for a badge, button, pin or similar article, as shown.

In testimony whereof I affix my signature.

RICHARD H. ALLAN.
